CLAIM

The ornamental design for a control panel as shown and described.

DESCRIPTION

FIG. 1 is a first isometric view of a control panel;
FIG. 2 is a second isometric view of the control panel;
FIG. 3 is a front elevational view of the control panel;
FIG. 4 is a rear elevational view of the control panel;
FIG. 5 is a top plan view of the control panel;
FIG. 6 is a bottom plan view of the control panel;
FIG. 7 is a left side elevational view of the control panel;
and,
FIG. 8 is a right side elevational view of the control panel.
The broken lines in the Figures show portions of a control panel that form no part of the claimed design.
